INVENTOR.
Hermine Eichbaum Mertz
BY *S. Webster*
ATTORNEY.

UNITED STATES PATENT OFFICE.

HERMINE EICHBAUM MERTZ, OF FARMINGTON, CALIFORNIA.

PRONG-FASTENER FOR GOWN DECORATIONS.

1,294,931.

Specification of Letters Patent.

Patented Feb. 18, 1919.

Application filed September 24, 1917. Serial No. 192,842.

To all whom it may concern:

Be it known that I, HERMINE EICHBAUM MERTZ, a citizen of the United States, residing at Farmington, in the county of San Joaquin, State of California, have invented certain new and useful Improvements in Prong-Fasteners for Gown Decorations; and I do declare the following to be a full, clear, and exact description of the same, reference being had to the accompanying drawings, and to the characters of reference marked thereon, which form a part of this application.

This invention relates to improvements in fasteners for securing ornaments, such as buttons, buckles, braid, flouncing, etc., to gowns. The object of the invention is to provide a means of detachably fastening ornaments to the gown, so that a multi-form gown may be produced, merely by interchanging the ornamentation thereon.

A further object of the invention is to produce a simple and inexpensive device and yet one which will be exceedingly effective for the purposes for which it is designed.

These objects I accomplish by means of such structure and relative arrangement of parts as will fully appear by a perusal of the following specification and claims.

30 In the drawings similar characters of reference indicate corresponding parts in the several views.

Figure 1 is a front elevation of my improved fastener, *per se*.

35 Fig. 2 is a rear elevation of the same.

Fig. 3 is a front elevation, showing the adaptation of the fastener for the purpose of applying braid, tape, flouncing or similar ornamentations to the gown.

40 Fig. 4 is a rear elevation of the subject matter shown in Fig. 3.

Fig. 5 is a front elevation of the fastener especially adapted for securing sewed-on buttons or similar ornaments.

45 Fig. 6 is a rear elevation of the subject matter shown in Fig. 5.

Fig. 7 is a perspective view of the fastener as applied to ready made buttons.

50 Fig. 8 is an inner-face view of a protecting disk adapted to be placed over the fastening prongs, to prevent the same from engaging the skin of the wearer.

Fig. 9 is a prong receiving disk arranged to be interposed between the disk shown in Fig. 8, and the cloth of the gown.

55 Fig. 10 is a bottom plan view, partly

broken out, showing the combination of the structure shown in Figs. 8 and 9.

Referring now more particularly to the characters of reference on the drawings, numeral 1 designates the body of the main form of my improved fastener. This embodies two members crossing each other at right angles, the whole being bound together by an annular wire 2. The body 60 members 1 are provided with projecting points 3. In practice, the ornaments, which may be anything desired, are sewed on to the cross members of the said body 1, and then, by means of the prongs 3, the same 65 may be removably fastened to the gown at any desired point, or in any desired manner.

In Fig. 3 I show the adaptation of the fastener to decorations having considerable 75 length, such as braid, tape, flouncing and the like. In this adaptation of the invention, the body members 1^a are spaced from each other in parallel relation, and the binding wire 2^a extends across the same at right 80 angles thereto. The prongs 3^a project beyond the wire 2^a.

The ornament is sewed to the parallel members 1^a, and the prongs are then used in detachably fastening the same.

The structure shown in Fig. 5 is used as a fastener for sewed-on buttons. In this figure, the body 1^b consists of an annular disk, provided with a central elongated slot 4. The wire 2^b is crimped underneath the outer 90 edges of the disk 1^b, and extends across the slot. The fastening prongs 3^b project outwardly from the periphery of the disk 1^b. The ornament is sewed by means of the thread being extended through the slot 4 95 and sewed around the wire 2^b. The same is then detachably fastened to the gown by means of the prongs 3^b.

In Fig. 7 the fastener is shown the same as in Figs. 5 and 6, but in this latter view 100 is shown a ready made button fixed to the fastener. In this view, 1^c designates the body of the fastener provided with a slot 4^c, and prongs 3^c. A looped wire 2^c is fixed across the slot 4^c, while the button 5 is permanently attached to the wire 2^c by means of an eye 6. This form of button may likewise be detachably fastened to the gown by means of the prong 3^c.

In Figs. 8, 9 and 10, I show a protecting 110 cover for the prongs of the fastener. This structure embodies an outer disk 7, having

- V shaped incisions 8. Turnably riveted to the disk 7 is an inner disk 9, provided with grooves 10, in its face adapted to be moved into or out of register with the incisions 8. 5 As the disk 9 is turned relative to the disk 7, the incisions 8 are brought into register with the grooves 10.

The prongs of the fastener being bent at right angles and pressed through the cloth 10 of the garment, the cover device is then inserted between the prongs with the disk 9 against the cloth. The prongs are then bent down through the incisions 8 in the disk 7, till they rest in the grooves 10. The disk 15 7 is then turned to move the incisions 8 therein out of register with the grooves 10, and this leaves the prongs held in the grooves and covered by the solid portion of the disk 7.

20 From the foregoing description it will be readily seen that I have produced such a device as substantially fulfills the object of the invention as set forth herein.

While this specification sets forth in detail the present and preferred construction of the device, still in practice such deviations from such detail may be resorted to as do not form a departure from the spirit of

the invention, as defined by the appended claims.

Having thus described my invention what I claim as new and useful and desire to secure by Letters Patent is:

1. A fastener comprising a body member provided with a central slot, a wire fixed to the body member and extending lengthwise across the slot whereby buttons or other articles may be attached thereto, and prongs projecting from the edges of the body and adapted to be pressed through the cloth of a garment and be bent over inwardly when pressed therethrough. 30

2. A fastener comprising a body member having projecting prongs, and means for covering the prongs when bent, such means comprising a disk having grooves, a second disk turnable on the first disk and provided with incisions arranged to be brought into register with the grooves whereby the prongs may be bent through the incisions 40 and into the grooves, the second disk then being turned to move the incisions out of register with the grooves and to cover the prongs. 45

In testimony whereof I affix my signature.

HERMINE EICHBAUM MERTZ.

Copies of this patent may be obtained for five cents each, by addressing the "Commissioner of Patents, Washington, D. C."
